Are bone conduction headphones good enough yet?, announced Oct. 24, 2016 [online], [retrieved Jan. 29, 2019]. Available from Internet, URL: <<https://www.theverge.com/2016/10/24/13383616/bone-conduction-headphones-best-pair-aftershokz>> (Year: 2016).*

Primary Examiner — Barbara Fox*Assistant Examiner* — Dana K Weiland(74) *Attorney, Agent, or Firm* — Birch, Stewart, Kolasch & Birch, LLP(57) **CLAIM**

The ornamental design for a wireless earphone, as shown and described.

DESCRIPTION

1. Wireless earphone

1.1 : Perspective

1.2 : Front

1.3 : Back

1.4 : Left

1.5 : Right

1.6 : Top

1.7 : Bottom

1.8 : Reference

Reproduction 1.8 is a reference view showing a state of use in which the wireless earphone is inserted into an ear. The broken line showing of the ear in Reproduction 1.8 forms no part of the claimed design.

1 Claim, 8 Drawing Sheets(56)
